UNITED STATES PATENT OFFICE

GLENN E. McFADDEN, OF BUFFALO, NEW YORK, ASSIGNOR TO MARKEL ELECTRIC PRODUCTS, OF BUFFALO, NEW YORK, A CORPORATION OF NEW YORK

DESIGN FOR A WALL BRACKET ELECTRIC LIGHTING FIXTURE

Application filed March 17, 1931. Serial No. 39,125. Term of patent 3½ years.

To all whom it may concern:

Be it known that I, GLENN E. McFADDEN, a citizen of the United States, residing at Buffalo, in the county of Erie and State of New York, have invented a new, original, and ornamental Design for a Wall Bracket Electric Lighting Fixture, of which the following is a specification, reference being had to the accompanying drawings, forming part thereof.

In said drawings:

Figure 1 is a diagrammatic top plan view of a wall bracket lighting fixture for the purpose of indicating contour.

Figure 2 is a front elevation of the same, it being understood that the half of the figure shown in dot and dash outline is to be similarly ornamented as the half fully illustrated and the lamp shades are shown in dot and dash lines.

I claim:

The ornamental design for a wall bracket electric lighting fixture, substantially as shown and described.

GLENN E. McFADDEN.
